UNITED STATES PATENT OFFICE.

JOHN C. KUPFERLE, OF ST. LOUIS, MISSOURI.

DOOR-HANGER.

SPECIFICATION forming part of Letters Patent No. 344,914, dated July 6, 1886.

Application filed February 1, 1886. Serial No. 190,442. (Model.)

To all whom it may concern:

Be it known that I, JOHN C. KUPFERLE, of St. Louis, Missouri, have made a new and useful Improvement in Door-Hangers, of 5 which the following is a full, clear, and exact description.

The improvement relates to the means provided for reducing the friction of the movement of the hanger-rollers, and also to the 10 means for adjusting the hanger.

In the annexed drawings, making part of 15 this specification, and exhibiting the improved hanger, Figure 1 is a vertical section on the line 1 1 of Fig. 2. Fig. 2 is an end elevation of the hanger. Fig. 3 is a side elevation of the hanger attached to a door. The outer upper corner only of the door is shown, and the wood-work above is shown in section. Fig. 4 is a view showing the hanger, 20 in end elevation, attached to the door, the view being of the opposite end of the hanger to that shown in Fig. 2 and the wood-work overhead being in section.

The same letters of reference denote the 25 same parts.

The improved hanger consists, mainly, of the hanger-frame A, a roller, B, journaled in the upper part of the hanger-frame at b, and a pair of rollers, C C', attached to an axle, C², 30 which is confined in the hanger-frame beneath the roller B, the hanger-frame being shaped out at c to receive the axle C², and while allowing the axle to revolve hold it from being displaced from beneath the roller B, when the last-named part is rotated by reason of moving the door.

The bearing b is in the upper end of the arm a of the hanger-frame, and the box c is vertically beneath the bearing b, and is contained in the portion a' of the hanger-frame. The box c extends sufficiently downward to prevent the axle, when the hanger-frame is dropped so as to cause the roller B to bear upon the axle, from bearing downward upon 45 the bottom of the box.

The portions a a' of the hanger-frame constitute a single part, in practice a single casting which is vertically adjustable with reference to the door in the following manner: a² 50 represents that part of the hanger-frame which is attached to the door D, the part a' being laid upon the top of the door at its corner and being fastened to the door by any suitable method—such as the screws E pass-

ing downward through the part and into the 55 door, as indicated in Fig. 3. The part a' inclines upward at its end a³. The parts a' and a² are connected by means of the link a⁴ and the screw-bolt a⁵. The link is jointed at one end to the part a' and at the other end to the 60 part a². The screw-bolt passes upward through the inclined end a³ of the part a', and its threaded portion engages in the part a'. By screwing the bolt a⁵ into the part a', that part a' carrying the various rollers above 65 named is drawn downward toward the part a², and by unscrewing the bolt the part a² is lowered away from the part above. The link a⁴ coacts with the screw-bolt by directing the movement of that end a⁶ of the part a' as the 70 opposite end, a⁷, is acted upon by the screw-bolt. When the hanger is attached to the door and all the parts are in position, as shown in Figs. 3, 4, the rollers C C' rest, and are adapted to be rolled upon the track-rails 75 F F', respectively, and the roller B bears upon the axle C², and the two parts—the roller B and the axle C²—are adapted to roll upon each other. The axle, now, as shown more 80 distinctly in Fig. 1, does not bear downward 85 in the box c, but is merely confined laterally at the points c' c' therein, and hence the friction of the axle within the box c is so slight as not to practically impede the movement of the door. Then when the door is moved, the 85 roller B and axle C² roll upon each other, and the rollers C C' roll upon the rails F F', and in consequence the door can be moved more readily than when the axle C² bears upward 90 against a fixed bearing in the hanger-frame.

So far as this feature of the improvement is concerned—namely, the use of a roller-bearing in combination with the roller-axle C²—the improvement is adaptable to any form of door, as well as to hangers of other descriptions. 95

I claim—

The combination of the part a', having the box c, the part a², the link a⁴, and the screw-bolt a⁵, with the upper roller, B, journaled at 100 b, the lower rollers, C C', and axle C², all substantially as described.

Witness my hand this 27th of January, 1886.

JOHN C. KUPFERLE.
